UNITED STATES PATENT OFFICE.

DANIEL J. SCHNEIDER, OF ROCHESTER, NEW YORK.

FLEXIBLE WIRE BRUSH.

1,294,180.

Specification of Letters Patent. Patented Feb. 11, 1919.

Application filed April 16, 1918. Serial No. 228,947.

To all whom it may concern:

Be it known that I, DANIEL J. SCHNEIDER, a citizen of the United States, residing at Rochester, in the county of Monroe and 5 State of New York, have invented a new and useful Flexible Wire Brush to be Worked in Numbers, Arranged and Fastened Over a Certain Surface, or to be Worked Single. The following is a specification of it.

My invention relates to a brush for cleaning surfaces of removable matter—the brush being made of any gage or shape of wire worked into wire fabric with open meshes, 15 the size and shape of wire and meshes varying for the different purposes—the open metal wire meshes are woven, braided, spun or accomplished in some other way and finished into sheets or rolls from which the 20 brushes are made. and the object of my invention is to produce a stiff, strong, yet flexible brush to remove substances by brushing them away by force.

I attain my object for this kind of a brush 25 by twisting, rolling, folding up or bringing otherwise together a sheet of metal wire fabric along axis 6—7 as illustrated in the accompanying drawing in which—

Figure 1. shows a front view.

Fig. 2. shows a side view thereof, particularly of the side where the sheet of metal wire fabric will be soldered together.

Fig. 3. shows a section of Fig. 1 along line 10—11.

Fig. 4 is a fragmentary view of a modified form.

Similar numerals refer to similar parts throughout the several views.

After the sheet of wire fabric 3 is folded, 40 twisted, rolled or in any other way brought tight or loosely together along axis 6—7 leaving the edge part 9 round or square, the part 2 is compressed along axis 6—7 into a round stem, this leaves part 1 in a brush 45 form with flexible elasticity while part 2 resists bending. Part 2 forms a grip to part 1. Part 2 may also be made separately or of different material and joined permanently with part 1, as shown in Fig. 4.

50 I prefer to roll up the wire fabric 3 as

shown in section Fig. 3 not exposing any cut through wire ends along meeting of part 4 and part 5, and in a way so the wires in the wire fabric part 3 of part 1 run diagonally to vertical axis, but it may be folded, rolled, twisted or forced together along axis 6—7 in some other way than shown in section Fig. 3.

After the two wire fabric edges, parts 4 and 5 of part 3 along axis 6—7 are firmly joined, they are fastened permanently together solid as shown at part 8, Fig. 3.

I prefer to solder part 4 onto part 5 while part 2, after it is compressed along axis 6—7 to form a substantial stem, I prefer to dip it into fluid hot metal to stiffen it further, but some other means may be employed of fastening part 4 onto part 5 permanently solid and also the further stiffening of part 2 may be done in a different way.

I am not aware that wire fabric ever was used for such a purpose and in such a manner, and I do not claim any particular way of forcing part 1 into a brush shape nor do I claim for a particular process of fastening 75 permanently solid together the edges of the wire fabric parts 4 and 5 of part 3, nor for the process of stiffening part 2 further after it is compressed to form a substantial stem.

But I claim—

1. A brush of the class described, comprising a flexible lower body and a compressed upper body, forming a handle, all consisting of open meshed metal wire fabric folded with the cut edges positioned in the 85 interior of the two bodies, the adjacent outer edges of the wire fabric being permanently fastened together, and the lower body tapering slightly toward the upper body.

2. A brush of the class described, comprising a flexible lower body and a compressed upper body forming a handle, all consisting of open meshed metal wire fabric folded with the adjacent outer edges of the wire fabric being permanently fastened together, the wires in the fabric of the lower body running obliquely to the vertical axis, and the lower body tapering slightly toward the upper body.

DANIEL J. SCHNEIDER.
